(57) **CLAIM**

The ornamental design for an electronic device, as shown and described.

DESCRIPTION

FIG. 1 is a perspective view of an electronic device, showing our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof;

FIG. 7 is a bottom plan view thereof;

FIG. 8 is another perspective view of the electronic device in an alternate position;

FIG. 9 is a front elevation view of FIG. 8 seen from a direction A;

FIG. 10 is a rear elevation view of FIG. 8 seen from a direction B opposite to the direction A;

FIG. 11 is a side elevation view of FIG. 8 seen from a direction C;

FIG. 12 is another side elevation view of FIG. 8 from a direction D opposite to the direction C;

FIG. 13 is a top plan view of FIG. 8 seen from a direction E; and,

FIG. 14 is a bottom plan view of FIG. 8 seen from a direction F opposite to the direction E.

The broken lines are for environmental purpose only and form no part of the claimed design.

The dash-dot lines represent an unclaimed boundary line and form no part of the claimed design.

1 Claim, 14 Drawing Sheets
